UNITED STATES PATENT OFFICE.

JESSE A. B. SMITH, OF STAMFORD, CONNECTICUT, ASSIGNOR TO UNDERWOOD TYPE-WRITER COMPANY, OF NEW YORK, N. Y., A CORPORATION OF DELAWARE.

TYPEWRITING MACHINE.

Application filed December 11, 1925. Serial No. 74,668.

This invention relates to work-sheet handling devices for typewriting machines, and is shown as applied to an Underwood twin-platen machine.

5 In some systems of typewriting book-keeping, it is sometimes desired to fill out a bill-sheet which is inserted around one of the platens, and then to copy the total of the bill upon a ledger-sheet on the other 10 platen, said total being manifolded upon a tally-strip which is permanently left in the machine.

In trying to feed a tally-strip which is wider than the ledger, a difficulty arises, because the tally-strip cannot be fed independently of the ledger as heretofore. It has been customary to provide a tally-strip behind a ledger-sheet for the purpose of copying a portion of the data typed upon the 20 ledger, and in such cases the tally-strip is made narrower than the ledger, and by eliminating the center feed-rolls it is possible to line space the same by means of a positively driven rewind spool. The ledger-sheet is line spaced by means of the regular feed-rolls engaging the borders of the ledger, the feed-rolls being, of course, arranged to clear the tally-strip. Since it is desired to use a wide tally-strip in this invention, 25 it will be clear that such a receiving spool could not be used in connection with the feed-rolls, because the ratio of feed on the spool is variable, whereas the ratio of feed on the platen is constant, and, of course, the strip would either sag or break, depending 30 on the size of the receiving spool.

In order to remedy this condition it is proposed to eliminate the receiving spool, and to feed the tally-strip, together with the 40 ledger-sheet, by means of the feed-rolls, the tally-strip being permitted to recoil itself into a roll of suitable size, which is torn off against a knife at convenient intervals.

In this invention novel means are provided for handling such work, the means being in the nature of an attachment for machines provided with two platens. According to certain features of this invention the tally-strip is inserted, together with a strip 45 of carbon in front thereof, around the right-hand platen to which it is fed from a supply-spool at the rear of the machine, means being provided, at the delivery side of the platen, for guiding the strip upwardly to a point where it is automatically refolded

upon a supporting shelf. The tally-strip is held on the platen by means of paper-fingers, and the feed-rolls of the machine are released in order that the ledger-sheet may be positioned to the printing point with 60 the aid of a front paper-table, upon which the ledger-sheet is held in printing position by means of a paper-finger or resilient clamp.

The bill-sheet is inserted around the left-hand platen in the regular manner and is positioned to the printing point, and then the feed-rolls are thrown on, thereby clamping all the sheets in the machine in printing 65 position.

In said twin-platen machines it is customary to provide a double line-spacing mechanism, one for each platen, so that the bill-sheet may be typed and line-spaced while the ledger-sheet is held stationary. After all the items are typed on the bill-sheet the total amount is typed, and the platen is moved to present the ledger-sheet to the printing point, so that the total and possibly some identification mark may be 70 typed on the tally-strip. The platen is then line-spaced to position the tally-strip for the first line of typing and the feed-rolls are released to withdraw both the bill and the ledger-sheets.

One of the features of this invention relates to novel means for feeding and rewinding the tally-strip, the usual rewinding spool having been dispensed with, so as to permit the tearing off of portions of the tally-strip, as may be required from time to time. The tally-strip is guided against a plate at the delivery side of the platen and the strip is permitted to recoil itself into a roll of suitable length. It is customary to run the 75 length of the strips to about one foot, which usually assembles all the daily totals of the bills sent to the various customers.

Another feature of this invention relates to means for facilitating the tearing off of the tally-strip. To this end, there is provided a knife secured to a front table at the top edge thereof. Said knife extends the full width of the tally-strip and is adjustably mounted on the front table to permit the handling of ledger-sheets of various widths.

In this particular embodiment of the invention it is desired that the identification numeral appearing in front of each item,

entered upon the tally-strip, be left out of the ledger-sheet, because the latter is usually provided with a suitable heading for each customer. To this end, it is proposed to 5 make the ledger-sheet narrower than the tally-strip thus leaving a margin at one side of the ledger, upon which margin the identification numeral may be typed.

This invention is in the nature of an improvement upon features disclosed in co-pending application No. 112,226, filed May 28, 1926.

Other features and advantages will hereinafter appear.

15 In the accompanying drawings,

Figure 1 is a cross-sectional view, in elevation, through the center of an Underwood typewriting machine, showing the work-sheets around the platen, the feed-rolls being in their effective position. Said view is 20 taken on line 1—1 of Figure 4.

Figure 2 is a diagrammatic front view, in elevation, showing all the work-sheets around the platen in typing position.

25 Figure 3 is a diagrammatic view, in elevation, showing the feed-rolls in their ineffective position, the work-sheet being held against the table by means of a resilient paper-finger.

30 Figure 4 is a front view, in elevation, showing the invention applied to an Underwood twin-platen typewriting machine.

Figure 5 is a detail, showing the construction of the tally-strip supply-spool.

35 This invention is applied to an Underwood twin-platen machine, such as disclosed in the patent to T. J. Coo, 1,539,384, dated May 26, 1925. Said machine includes a pair of platens 10 and 11 mounted on a platen-40 axle 12, which is supported by end plates 13 and 14 of a platen-frame which is borne by a carriage, not shown. The platen 10 is connected by means of a tubing 15 to a finger-wheel 16, and may be rotated independently 45 of the other platen. The platen 11 is fast to the axle 12 by means of a screw 17, the axle carrying fast thereto another finger-wheel 18. By means of this arrangement it is possible to rotate either platen independently of the other.

According to the method of handling the work in this invention, a tally-strip 19, having a superposed strip of carbon 20, is drawn down from a supply-spool 21 mounted on a 55 shaft 22, the ends of both strips being inserted at the rear of the platen around the same, and up in front thereof. The tally-strip is passed under paper-fingers 23, bearing on the platen, and is then led up over a table 24, which serves as a backing to prevent the curling of the tally-strip. Owing to the natural tendency of the paper to curl itself, once having been wound on a spool for some time, the same is permitted to be recurled 60 upon a supporting shelf 25. The paper-

fingers are provided with pressure rollers 26, and may be swung into and out of position in the regular manner. Said paper-fingers are slidably mounted on a shaft 27 which serves as a brace for the end plates 13 and 14 of the platen frame.

Previously to inserting the tally-strip, the usual feed-rolls 28 are released, the tally-strip being held in place by means of the paper-fingers 23. The feed-rolls are rotatably mounted upon shafts 29, extending the full length of both platens, so that the feed-rolls may be simultaneously operated for both platens.

80 A ledger-sheet 30 is then inserted at the rear of the platen under the same and is led over a front table 31 to be laterally positioned, by means of side gages 32, and also positioned to the printing line by gaging the same against front scales 33, whereupon a pressure finger 34 is swung into operated position, as shown in Figure 1, to hold the ledger-sheet while a bill sheet 35 is inserted 85 around the platen 10 in the regular manner, the feed-rolls being then cast on, to permit 90 the line feeding of the bill-sheet.

95 The table 31 is made in two sections to provide lateral adjustment for the ledger sheet, and is secured to a cross-bar 36 by means of screws 37 passing through elongated slots 38 in the table. The cross-bar 36 is supported at the ends thereof by means of brackets 39 mounted on the shaft 27 and on a shaft 40, the latter being fast to end plates 41 which are in turn secured to the plates 13 and 14 of the platen frame by means of screws 42. The cross-bar is provided with slots 43 so that the same may be removed from the brackets without necessitating the withdrawing of supporting screws 44.

100 In order to facilitate the easy replacement of the supply spool 21, there is provided a pair of plates 45 pivotally mounted on the shaft 40, the plates being tied together by means of a tube 46 and a brace-rod 47. The tube 46 is secured to the plates 45 by means of screws 48 and carries, fast thereto, the table 24. By means of this arrangement, the supply-spool is easily replaced by 105 rotating the shaft 22, which is provided with a finger-piece 49, thereby presenting flattened portions 50 to slots 51 in the plates 41.

110 In order to facilitate the tearing off of portions of the tally-strip, there is provided a knife 52 fast to one of the sections of the table 31 by means of rivets 53. The other end of the knife is adjustably secured to the other section of the table by means of a screw 54 passing through an elongated slot 55 in said table and screwing into a tapped hole in the knife.

115 Referring more particularly to Figure 5, in which a longitudinal sectional view of the supply-spool is shown, it will be noted that 120

the same is provided with removable heads 57 designed to enter a tube 56 around which the tally-strip is wound. By means of this arrangement, the heads are withdrawn from 5 the used spool and are reinserted into the tube of a fresh spool when needed.

Variations may be resorted to within the scope of the invention, and portions of the improvements may be used without others.

10 Having thus described my invention, I claim:

1. In a typewriting machine, in combination, a platen, releasable feed rolls for feeding a work-sheet and a wider continuous 15 tally strip therearound, auxiliary feed rolls for holding the tally-strip while inserting the work-sheet in front thereof, and means for conducting the tally strip in a flat condition, at the delivery side of the platen, up 20 to a suitable housing to permit the natural recoiling of the tally strip.

2. In a typewriting machine, in combination, a platen, releasable feed rolls therefor, a supply spool at the rear of the platen, 25 means for conducting a tally strip on said supply spool to the platen, auxiliary feed rolls for holding said strip on the platen when the releasable feed rolls are thrown off, means including a front table for 30 positioning a work-sheet in front of said tally strip, and a second front table, behind the first-mentioned front table, for guiding the tally strip up to a receiving bracket on which it is recoiled owing to the bent condition 35 of the paper tissues acquired in the supply spool.

3. In a typewriting machine, in combination, a twin platen, releasable feed rolls therefor, a supply spool at the rear of one of 40 the platens, means for conducting a tally strip on said supply spool to said platen, auxiliary feed rolls for holding said strip on said platen when the releasable feed rolls are thrown off, means including a front table for 45 positioning a work-sheet in front of said tally strip, and means for resiliently holding said work-sheet on said front table so as to permit the insertion and positioning of a bill-sheet around the other platen.

50 4. In a typewriting machine, in combination, a platen, releasable feed rolls therefor, a supply spool around which a tally strip is wound, means for conducting said tally strip to the platen, auxiliary feed rolls on 55 said platen to hold the tally strip, means for guiding the tally strip in a flat condition, and a shelf to support the free end of the tally strip in a coiled condition.

60 5. In a typewriting machine, in combination, a platen, releasable feed rolls therefor, a supply spool around which a tally strip is wound, means for conducting said tally strip to the platen, auxiliary feed rolls on 65 said platen to hold the tally strip, means for guiding the tally strip in a flat condi-

tion, a shelf to support the free end of the tally strip in a coiled condition, and a knife adjacent said shelf, to permit the tearing off of portions of said tally strip.

6. In a typewriting machine, in combination, a platen, releasable feed rolls therefor, a supply spool around which a tally strip is wound, means for conducting said tally strip to the platen, auxiliary feed rolls on 70 said platen to hold the tally strip, a table for guiding the tally strip in a flat condition, a shelf to support the free end of the tally strip in a coiled condition, a front table having side edges for positioning a work-sheet in front of said tally strip, and a knife at the top edge of said front table for severing the tally strip in suitable 75 lengths.

7. The combination, in a typewriting machine, of a revoluble platen, releasable feed rolls cooperating therewith for feeding a work-sheet and an associated wider tally strip therearound, pressure rolls for holding the tally strip on the platen when positioning the work-sheet for the first line of typing, a spool on which the tally strip is wound, means for conducting the tally strip upwardly in a flat condition, and means for supporting the free end of the tally strip in 80 a manner to permit its being recoiled into 85 rolls of suitable lengths.

8. The combination, in a typewriting machine, of a revoluble platen, releasable feed rolls cooperating therewith for feeding a work-sheet and an associated wider tally strip therearound, pressure rolls for holding the tally strip on the platen when positioning the work-sheet for the first line of typing, a supply spool at the introductory side 90 of the platen on which the tally strip is wound, means for conducting said tally strip to the platen, a table, at the delivery side of the platen, for positioning the work-sheet, and means for resiliently holding said work-sheet on said table when the feed rolls are released to insert another work-sheet 95 around the platen.

9. The combination, in a typewriting machine, of a revoluble platen, feed rolls for simultaneously feeding a tally strip and a narrower associated work-sheet, means for holding the tally strip when the feed rolls are released to insert the work-sheet, a front table at the delivery side of the platen for laterally positioning the work-sheet, means for conducting the tally strip in a flat condition behind the front table, and a knife fast to the upper edge of said table for tearing off the tally strip.

10. The combination, in a typewriting machine, of a revoluble platen, feed rolls for simultaneously feeding a tally strip and a narrower associated work-sheet, means for holding the tally strip when the feed rolls are released to insert the work-sheet, a front 125
